(57) CLAIM

The ornamental design of a headgear clip for respiratory mask, as shown and described.

DESCRIPTION

FIG. 1 is a perspective illustration of a first embodiment of a headgear clip for respiratory mask according to our design; FIG. 2 is a front view thereof; FIG. 3 is a rear view thereof; FIG. 4 is a right side view thereof; FIG. 5 is a left side view thereof; FIG. 6 is a top view thereof; FIG. 7 is a bottom view thereof; and, FIG. 8 is a perspective view of the headgear clip in position on a respiratory mask.

Where included, broken lines showing environment or structure are for illustrative purposes only and form no part of the claimed design.
